UNITED STATES PATENT OFFICE.

JOHN F. O'CONNOR, OF CHICAGO, ILLINOIS, ASSIGNOR TO WILLIAM H. MINER, OF CHICAGO, ILLINOIS.

HIGH-CAPACITY TWIN-FRICTION DRAFT-GEAR.

1,130,998.

Specification of Letters Patent.

Patented Mar. 9, 1915.

Application filed December 13, 1913. Serial No. 806,390.

To all whom it may concern:

Be it known that I, JOHN F. O'CONNOR, a citizen of the United States, residing in Chicago, in the county of Cook and State of Illinois, have invented a new and useful Improvement in High-Capacity Twin-Friction Draft-Gears, of which the following is a specification.

This invention relates to improvements in 10 high capacity twin friction draft gears.

One object of the invention is to provide a draft gear for railway cars of high capacity having a twin arrangement of friction mechanisms in combination with preliminary compression devices.

Another object of the invention is to provide a gear of the type above indicated in which the twin sets of friction mechanisms are arranged vertically one above the other.

20 The invention furthermore consists in the improvements in the parts and devices and in the novel combinations of the parts and devices herein shown, described or claimed.

In the drawing forming a part of this 25 specification, Figure 1 is a part plan and part horizontal section on the line 1—1 of Fig. 2, of a draft gear embodying my improvements. Fig. 2 is a part side elevation and part vertical section on line 2—2 of 30 Fig. 1. Fig. 3 is a transverse vertical section taken on the line 3—3 of Fig. 1 and Figs. 4 and 5 are detail perspective views of the two cases.

In said drawing 10, 10 denote the center 35 sills, the same having secured thereto upper and lower sets of front stops 13, said stops and sills being slotted to receive a key 14 therethrough and to permit the same to slide freely backward and forward therein. The 40 key 14 unites the rear end of the coupler 15 to a pair of longitudinally extending links 16, the latter being also slotted as at 17 to receive the key 14 and also to permit it to slide rearwardly therein. The center sills 45 are also slotted as at 18 and surrounding the slots on the outsides of the sills and secured thereto are castings 19 each provided with a flange 20 forming a slot 21 in which is slidably mounted another key 22, the latter 50 also passing through suitable slots in the links 16, see Fig. 1. As will be understood, the links 16 and key 22 form a yoke which acts in the usual manner. The rear end of the draw-bar abuts the front follower 23 55 which is vertically elongated and on its rear face engages a pair of wedges or spreaders

24 of two friction mechanisms, hereinafter described.

The draft gear proper comprises a main case 25 having a pair of parallelly arranged 60 spring chambers or pockets 26, one above the other; a pair of similarly arranged friction shells 27 in each of which are slidably mounted a plurality of friction shoes 28, each set of shoes co-operating with a wedge or spreader 65 24. Each spring chamber has located therein a pair of nested main springs 29 and 30 operating against the rear ends of the friction shoes to resist movement thereof. A pair of retaining bolts 31 are also provided 70 which extend through the friction elements and the rear wall 32 of the casing 25. From the rear wall 32 of the casing 25 extend a pair of parallel cylindrical spring pockets 33, see Fig. 4, in each of which is 75 adapted to be seated a pair of nested preliminary compression springs 34, the opposite ends of said springs 34 of each set being engaged by the inner face of the rear wall 35 of another casing 36 which is provided 80 with cylindrical pockets 37, 37 that telescope over the spring chambers 33 of the main casing 25. The casing 36 is provided with a pair of forwardly extending arms or wings 38 which slide and operate in correspondingly shaped and located grooves or 85 channels 39 centrally located on the sides of the main casing 25. The arms 38 and the web of the main casing 25 between the two sets of upper and lower spring chambers are slotted, respectively, at 40 and 41 through which the key 22 extends, it being noted that the slots 40 and 41 are longer than the width of the key 22 to permit the latter to have movement therein. The parts 90 95 are adapted to be suitably supported by means of a saddle plate 44 which may be of usual construction and attached in the ordinary manner.

The parts are assembled as indicated in the drawing and, as will be evident, the key 22 engages the rear portions of the flanges 20 of the casings 19 and the preliminary or auxiliary compression springs 34 will hold the two casings 25 and 36 separated to the extent indicated most clearly in Fig. 2. At the same time the wedges or spreaders of the friction mechanisms will be in firm engagement with the rear side of the front follower 23.

100 The operation is as follows: Under buff, 105 the draw-bar will push the front follower 110

23 backward, which in turn will cause a bodily movement of the main casing 25 with the main springs and friction mechanisms contained therein since the resistance of 5 these parts to compression is greater than the resistance of the sets of springs 34. During buffing movement, the casing 36, which acts as a rear follower, will be prevented from rearward movement on account of the key 22 and accordingly the 10 springs 34 will be compressed until the shoulders 42 of the main casing 25 come into contact with the co-operating shoulders or abutments 43 on the other casing 36, this 15 action preventing setting or over-compression of the springs 34. At this point in the operation, the casing 25 will be prevented from further rearward movement and the friction mechanisms therein will come into 20 action, thus absorbing the greater part of the buffing shock. Under pull, the draw-bar through the key 14 will pull the links 16 and key 22 forwardly, the front follower being held by the front stops 13. During 25 the first part of the pulling movement the main casing 25 will be held stationary until the preliminary springs 34 are compressed and the two casings 25 and 36 telescoped to the fullest extent. A continued forward 30 movement causes the two casings 25 and 36 to move in unison, thus bringing the twin sets of friction mechanisms into action.

From the preceding description it will be seen that the gear which I have provided is 35 of extremely high capacity and yet is so arranged that it has an easy starting action under either buff or pull. It will also be noted that the forces transmitted to the gear under buff are applied centrally to the 40 front follower and that the resistance to the latter's movement by the wedges or spreaders 24 is exerted relatively near to the center line of thrust, thus minimizing the bending forces on the front follower. 45 By removing the back key 22, the rear casing 36 with the preliminary compression springs associated therewith may also be removed without the necessity of removing the main casing 25. The entire arrangement is also very compact and easy to install.

Although I have herein shown and described what I now consider the preferred embodiment of my improvement, yet it will be understood that various changes and modifications may be made without departing from the spirit of the invention, and all such changes and modifications are contemplated as come within the scope of the 55 60 claims appended hereto.

I claim:

1. In a draft gear, in combination: a

draw-bar; links connected therewith; two casings longitudinally movable with respect to each other and having preliminary compression springs interposed therebetween; a key connecting said links and passing through slots in both of said casings; and twin arranged friction mechanisms in one of said casings, substantially as specified. 65 70

2. A draft gear including, in combination: a draw-bar; a front follower; links connected with said draw-bar; a casing having main spring chambers in twin arrangement therewith one above the other, said casing having also friction shells in alignment with the spring chambers; springs within said chambers; friction shoes and spreaders within the friction shells, the spreaders being in engagement with the 80 front follower; another casing located at the rear of said first named casing; preliminary compression springs interposed between said casings; and a key connecting said casings and links, substantially as 85 specified.

3. In a draft gear, in combination: a draw-bar; two casings longitudinally movable with respect to each other; preliminary compression springs interposed between said 90 casings; a key passing through slots in both of said casings to thereby hold the same together; twin arranged friction mechanisms in one of said casings; and means connected with the draw-bar for operating said casings and compressing the springs and friction mechanisms. 95

4. In a draft gear for railway cars, a shell having forwardly opening chambers and rearwardly opening chambers, each in twin arrangement, a follower, preliminary springs in the rearwardly opening chambers bearing against the follower, compression resisting elements in each of the forwardly opening chambers, the shell being provided on either 100 side with a median groove between the chambers, the follower being provided with wings 105 adapted to reciprocate in said grooves.

5. In a draft gear for railway cars, a shell, chambers in said shell in twin arrangement, 110 compression resisting elements in each of said chambers, preliminary springs and a follower, the preliminary springs being seated between the follower and the shell, the shell being provided at either side with longitudinal grooves, the follower being provided with wings adapted to reciprocate in 115 said grooves.

Signed this 9th day of December, 1913,
in the presence of two witnesses.

JOHN F. O'CONNOR.
